US0D1031686S

(12) **United States Design Patent** (10) **Patent No.:** **US D1,031,686 S**
(45) **Date of Patent:** **** Jun. 18, 2024**

(54) **RADIO FRONT PANEL**

(71) Applicant: **Grace Digital Inc.**, Poway, CA (US)

(72) Inventors: **Greg William Fadul**, San Diego, CA (US); **James D. Palmer**, Poway, CA (US)

(73) Assignee: **Grace Digital Inc.**, Poway, CA (US)

(**) Term: **15 Years**

(21) Appl. No.: **29/844,677**

(22) Filed: **Jun. 30, 2022**

(51) LOC (14) Cl. **14-03**

(52) U.S. Cl.

USPC **D14/157**; D14/258
